UNITED STATES PATENT OFFICE.

JOHN O. HEINZE, OF DETROIT, MICHIGAN, ASSIGNOR TO THE JOHN O. HEINZE COMPANY, OF SPRINGFIELD, OHIO, A CORPORATION OF OHIO.

ELECTRIC STARTER AND GENERATOR.

1,287,304.

Specification of Letters Patent.

Patented Dec. 10, 1918.

Application filed March 22, 1915. Serial No. 16,239.

To all whom it may concern:

Be it known that I, JOHN O. HEINZE, a citizen of the United States of America, residing at Detroit, in the county of Wayne and State of Michigan, have invented certain new and useful Improvements in Electric Starters and Generators, of which the following is a specification, reference being had therein to the accompanying drawings.

10 This invention relates to an electric generator and engine starter especially adapted for use on motor vehicles and its object is to provide a very simple, compact and efficient construction so arranged as to greatly simplify the means for connecting the same with an internal combustion engine to impart motion to the engine in starting and to drive the device as a generator after the engine has started. A further object is to provide certain other new and useful features, all as hereinafter more fully described, the invention consisting in part, in providing a tubular armature shaft with a longitudinally movable member extending there-

20 through for effecting a connection of the motor and generator with the engine, and further consisting in certain other matters hereinafter set forth and more particularly pointed out in the appended claims, reference being had to the accompanying drawing in which the figure represents a longitudinal section through a device embodying the invention and illustrating the manner of connecting the same to an internal combustion engine.

Within a suitable casing 1 is mounted the field coils 2 of an electric motor and the corresponding field coils 3 of a current generator, and bearings 4 and 5 are provided in the ends of the casing for a driving shaft 6 which extends through the tubular armature shafts 7 upon which are mounted the armatures 8 and 9 of the motor and generator respectively. The tubular shafts and driving shaft are grooved to receive a spline or key 10 for operatively connecting the same to turn together and to permit of a free longitudinal movement of the driving shaft through the tubular armature shafts.

50 Any suitable means may be provided for transmitting motion from the shaft 6 to the crank shaft of an engine and from the engine crank shaft to said shaft, such connection being preferably effected by a longitudinal movement of said shaft 6. In the

drawing, a simple and efficient arrangement is illustrated comprising a skew gear 11 secured upon one end of said shaft to be brought into mesh with a like gear 12 on the fly wheel or other convenient part of an engine when the shaft is moved endwise and the electric motor is energized, a suitable friction clutch 13 being provided at the opposite end of said longitudinally movable shaft to effect a driving connection between said shaft and a suitable train of gearing 14 or other suitable means for transmitting motion from the crank shaft 15 of the engine.

The shaft 6 is moved longitudinally in one direction and normally held with the members of the clutch 13 engaged, by means of a coiled spring 16 sleeved upon the shaft between the end of the casing and an enlargement 17 on the shaft, and to move said shaft in an opposite direction against the action of said spring and bring the gears 11 and 12 into mesh, an electro-magnet is formed by providing a magnetic coil 18 the outer end of which is connected by a wire 20 with the field of the motor and this coil encircles the shaft 6 and spring 16 within a tubular extension 19 on the end of the casing, to which extension the inner end of said coil is connected, the motor circuit and coil being thereby grounded. The shaft and enlargement 17 thereof forms the movable core or armature of the electro-magnet, the tubular extension or sleeve 19 forming a part of the magnetic circuit and said sleeve is preferably formed flaring near its outer end and the enlargement 17 correspondingly formed to decreasingly reduce the air gap between said sleeve and enlargement as the shaft is moved longitudinally upon energization of the coil. The coil of the electro-magnet being connected to the field of the motor, said coil is energized at once upon the energization of the motor to start the engine, and thus the shaft 6 will be automatically shifted to bring the gears 11 and 12 into mesh immediately upon the closing of the motor circuit switch or other controlling means (not shown), and in a like manner when the current to the motor is cut off, the magnet will be deenergized, permitting the spring 16 to operate to shift the shaft and bring the members of the friction clutch 13 into engagement. Preferably the parts are so proportioned that the members of the friction clutch 13 will be disengaged just before the

gears 11 and 12 come into mesh, and there is therefore no possibility of the shaft being connected to the engine at both ends at the same time, and in this arrangement, the 5 starter unit can be entirely disconnected if desired, any suitable means, not shown, being provided to hold the shaft in an intermediate position. The operator will open the motor circuit as soon as the engine begins to operate under its own power and the 10 immediate engagement of the clutch members will cause the transmission of motion from the gear train 14 which is operated by the engine shaft, to the shaft 6 upon which 15 the generator armature 9 is secured and the generation of current will at once begin.

By providing a tubular armature extending completely through the starting unit, any suitable member may be extended there- 20 through for effecting the engagement and disengagement of the means for transmitting motion to and from the engine, without the necessity for the providing of shifting means outside of and at each end of the 25 casing where a connection is made, as shown, at each end of the shaft. In the drawing means is shown at each end of the starting unit to transmit motion to and from the engine, and while this is the preferred con- 30 struction it may be found preferable in cer- tain installations to provide motion trans- mitting means at one end of the unit only, and it is not intended to limit this invention to the particular arrangement shown. The 35 drawing also shows a motor and a separate generator inclosed within a single casing which is the preferred construction but ap- plicant does not limit himself to this par- ticular construction and arrangement and 40 points out that other changes may be made within the scope of the appended claims and without departing from the spirit of the invention.

Having thus fully described my invention, 45 what I claim is:—

1. In an engine starter, the combination of a starting unit having an armature and a tubular armature shaft extending completely through the armature, and means for trans- 50 mitting motion to or from said armature to an engine including means movable longitudinally through said tubular shaft for making said motion transmitting means ef- fective for transmitting motion.

55 2. In an engine starter, the combination of a starting unit having an armature, and means for transmitting motion to or from said armature including a member extending through said armature and movable longi- 60 tudinally for making said motion transmitting means effective for transmitting motion.

3. In an engine starter, the combination of a starting unit having an armature, and means for transmitting motion to or from 65 said armature including a shaft operatively

connected to said armature to turn therewith and movable relatively thereto for making said motion transmitting means effective for transmitting motion.

4. In an engine starter, the combination of a starting unit having an armature, and means for transmitting motion to or from said armature including a shaft operatively connected to the armature to turn therewith and movable relatively thereto, and means operated by the movement of said shaft relative to said armature for making said motion transmitting means effective for transmitting motion.

5. In an engine starter, the combination of a starting unit having a tubular armature shaft, means for transmitting motion to or from said shaft to an engine including a driving shaft slidably in said tubular shaft and operatively connected thereto to turn therewith, and means operated by the sliding of said driving shaft for effecting an operative connection between said engine and driving shaft.

6. In an engine starter, the combination of a starting unit having a tubular armature, means for transmitting motion to and from said unit to an engine including a shaft extending through the tubular armature and operatively connected thereto to turn therewith and to have a movement independently thereof, and means operated by a relative movement of said shaft and armature to effect an operative connection between an engine and said armature.

7. In an engine starter, the combination of a starting unit having a tubular armature, means for transmitting motion to and from an engine including a shaft extending through the tubular armature and operatively connected thereto to turn therewith, and to have a movement independently thereof, and including means at each end of the armature operated by a relative movement between said shaft and armature for effecting the transmission of motion by said motion transmitting means.

8. The combination of a starting unit having a longitudinally movable armature shaft, means at one end of said unit for transmitting motion from one end of said shaft to an engine including a member carried by the shaft for effecting a positive driving connection with the shaft, means at the opposite end of said unit for transmitting motion from an engine to said shaft including friction clutch members one of which is carried by said shaft.

9. In an engine starter, the combination of a starting unit having an armature and a tubular shaft upon which the armature is mounted and which shaft extends entirely through the armature, motion transmitting means and means extending through and operatively connected to the tubular shaft to

- turn therewith and to move relatively thereto for effecting a discontinuance of the transmission of motion from either end thereof to said motion transmitting means.
- 5 10. The combination of a starting unit having a longitudinally movable shaft, and means at one end of said shaft for transmitting motion thereto to drive the unit, and means at the opposite end of the shaft for transmitting motion therefrom to an engine, said shaft being longitudinally movable for making said motion transmitting means at either end of the shaft effective to transmit motion.
- 15 11. The combination of a starting unit having a longitudinally movable armature shaft, means at each end of the shaft for transmitting motion between the shaft and an engine, including a member on each end 10 of the shaft for effecting an operative connection between the shaft and the motion transmitting means when the shaft is moved in either direction, and means for moving the shaft longitudinally.
- 5 12. The combination of a starting unit having a longitudinally movable armature shaft, means at each end of the shaft for transmitting motion between the shaft and an engine including a member on each end 10 of the shaft for effecting an operative connection between the shaft and the motion transmitting means when the shaft is moved in either direction, an electro-magnet for moving the shaft longitudinally in one direction, and a spring for moving the shaft longitudinally in an opposite direction.
18. The combination of a casing, fields of an electric power unit secured in the casing, a tubular armature, a member extending through the tubular armature and beyond the ends of the casing, means for transmitting motion between an engine and the armature at each end of the casing, and electro-magnetic means within the casing controlled by the power unit for operating the means extending through the tubular armature to effect an operative connection between the motion transmitting means and the armature.
14. The combination of a motor and a separate generator, each having a tubular armature shaft extending therethrough, a driving shaft extending therethrough and operatively connected thereto to turn therewith, said shaft being free to slide longitudinally 55 through the tubular shafts, means for transmitting motion between the driving shaft and an engine, and means for moving the driving shaft longitudinally to effect an operative connection between said shaft and 60 motion transmitting means.
15. The combination of a casing, a motor and a separate generator secured in the casing in axial alignment and arranged end to end, a tubular armature for said motor and 65 a tubular armature for the generator, bearings in the ends of the casing for said tubular armatures, a drive shaft in the tubular armatures operatively connected thereto to turn therewith and free to move longitudinally therethrough with its ends projecting beyond the ends of the tubular armatures, a gear on one end of the driving shaft, a gear 70 operatively connected to an engine to be engaged by the gear on the driving shaft, 75 means for transmitting motion between an engine and the opposite end of the driving shaft, a friction clutch to effect an operative connection between said means and the end of the driving shaft and adapted to be operated by a longitudinal movement of the shaft, an electromagnet for moving the driving shaft longitudinally in one direction, and a spring to move the shaft in an opposite direction and operate the friction clutch. 80
- 85 In testimony whereof I affix my signature in presence of two witnesses.
